(57) **CLAIM**

The ornamental design for a bottle warmer, as shown and described.

DESCRIPTION

FIG. 1 is a side view of a bottle warmer showing my new design.

FIG. 2 is a back view of the bottle warmer.

FIG. 3 is a front view of the bottle warmer.

FIG. 4 is a top view of the bottle warmer.

FIG. 5 is a bottom view of the bottle warmer; and,

FIG. 6 is a perspective view of the bottle warmer.

The broken lines shown in FIG. 1 are for illustrative purposes only and form no part of the claimed design.
